UNITED STATES PATENT OFFICE.

ARTHUR ROBERT KRAUSE, OF WOODHAVEN, NEW YORK, ASSIGNOR TO LION ELECTRIC MANUFACTURING CO. INC., A CORPORATION OF NEW YORK.

DESIGN FOR A HANGER FOR LIGHTING-FIXTURE GLOBES.

Application filed December 3, 1924. Serial No. 11,570. Term of patent 7 years.

To all whom it may concern:

Be it known that I, ARTHUR R. KRAUSE, of the hanger for lighting fixture globes, the a citizen of the United States, and a resident of Woodhaven, county of Queens, and State of New York, have invented a new, original, and ornamental Design for Hanger for Lighting-Fixture Globes, of which the following is a specification, reference being had to the accompanying drawing, forming a part hereof.

The drawing shows an elevational view portion indicated in full line outline being ornamented in the same manner as the portion more fully illustrated.

I claim:

The ornamental design for a hanger for lighting fixture globes substantially as shown and described.

ARTHUR ROBERT KRAUSE.
